UNITED STATES PATENT OFFICE.

LOUIS MARTAIN SARTAIN, OF COALMONT, TENNESSEE, ASSIGNOR OF THREE-TENTHS TO W. R. CURTIS, ONE-TENTH TO G. P. DYKES, ONE-TENTH TO J. J. GIVENS, ONE-TENTH TO J. A. GOFORTH, AND ONE-TENTH TO T. M. LOCKHART, ALL OF COALMONT, TENNESSEE.

RAIL-JOINT.

1,314,151.

Specification of Letters Patent. Patented Aug. 26, 1919.

Application filed February 5, 1919. Serial No. 275,144.

To all whom it may concern:

Be it known that I, LOUIS M. SARTAIN, a citizen of the United States, residing at Coalmont, in the county of Grundy and 5 State of Tennessee, have invented a new and useful Rail-Joint, of which the following is a specification.

This invention relates to rail joints, one of its objects being to provide rail gripping 10 elements adapted to be coupled in a novel manner to the tie plate thereunder and which, when subjected to the weight of the engaged rails and of the load thereon, will grip the rails with increased pressure, holding them tightly against displacement relative to each other.

A further object is to provide efficient 15 means for coupling said members to the plate thereunder, and which allows the members to be removed readily when the rail is removed.

With the foregoing and other objects in view which will appear as the description 20 proceeds, the invention consists of certain 25 novel details of construction and combinations of parts which will be hereinafter more fully described and pointed out in the claim, it being understood that various changes 30 may be made in the construction and arrangement of the parts without departing from the spirit or sacrificing any of the advantages of the invention as set forth in the appended claim.

In the accompanying drawings the preferred form of the invention has been shown.

In said drawings—

Figure 1 is a plan view of a portion of a tie plate having the present improvements in position thereon and engaging and holding 40 rails.

Fig. 2 is a side elevation of the structure, certain parts being shown partly in section.

Fig. 3 is a section on line 3—3, Fig. 2.

Fig. 4 is a perspective view of one end 45 portion of the tie plate.

Referring to the figures by characters of reference, 1 designates a plate that can be secured on a tie or other structure or that can be part of a metallic or composite tie.

This plate is adapted to extend under the 50 rails R at the joint and is provided at each side of the joint with upstanding shoulders 2 each of which has a recess 3 extending thereinto. Another recess 4 is formed in the top of the plate adjacent each shoulder 2 55 and these recesses 4 are adapted to receive lugs 5 extending downwardly from the free end portions of chair members 6. These members have ears at their inner ends, as shown at 7, which are pivotally connected as 60 shown at 8. Jaws are extended upwardly from the chair members close to the pivot 8 and each of these jaws, indicated at 9, is so shaped as to lap one of the base flanges of each rail R and to extend toward and into 65 contact with the webs of the rails. Recesses 10 are formed in the gripping faces of the jaws for the reception of the ends of dowel pins 11 which are extended through holes in the webs of the rails, as shown. Tongues 12 70 are extended from the outer ends of the members 6 and are insertible into the recesses 3.

In using the device the jaws 9 are swung 75 apart so as to cause the outer ends of the members 6 to swing downwardly toward each other. The tongues 12 are then inserted into the recesses 3. The rails R with the dowels therein are placed between the jaws and the weight of the rails, pressing 80 downwardly on the inner or connected ends of the members 6 will cause said members to move downwardly, thereby forcing the tongues 12 into the recesses 3, lowering the lugs 5 into the recesses 4 and causing the 85 jaws 9 to grip the rails tightly and receive the ends of the dowels 11. Thus the parts will be locked together securely and the only way in which the rails can be unfastened is by raising them and the inner ends of the 90 members 6 so as to swing the jaws apart.

What is claimed is:

The combination with a tie plate having spaced upstanding shoulders provided with recesses, there being recesses in the plate and adjacent the shoulders, of pivotally connected chair members having projecting means thereon for insertion into the respec-

tive recesses when the members are moved onto the tie plate, rail gripping jaws upon the members, and rail engaging dowels insertible at their ends into the opposed jaws, 5 those portions of the members between the jaws constituting rail supports.

In testimony that I claim the foregoing as

my own, I have hereto affixed my signature in the presence of two witnesses.

LOUIS MARTAIN SARTAIN.
